GAS BURNER FOR SPACE HEATING

Lee C. Sassenhausen, Warren, Ohio

Original application June 8, 1949, Serial No. 97,836, now Patent No. 2,694,445, dated November 16, 1954. Divided and this application September 17, 1954, Serial No. 456,722

1 Claim. (Cl. 158—113)

This invention relates to a gas burner and it has to do particularly with a gas burner for space heating purposes.

This application is a division of copending application of this inventor, Serial No. 97,836, filed June 8, 1949, now Patent No. 2,694,445, dated November 16, 1954. The gas burner structure of the present invention is admirably adapted as a conversion burner in the sense that it may be installed in a furnace which, previous thereto, was arranged to consume a different type of fuel, such as coal or oil, or the burner of the present invention may be used as a replacement for another gas burner. On the other hand, the burner of the present invention, and particularly some of the features thereof, may be employed with original equipment.

The general objects of the invention are to provide a simplified light weight burner and burner structure which can be manufactured economically so that the retail cost thereof may be reflected in the price to the ultimate purchaser and user. Due to its light weight it may be easily and economically transported. In connection with the weight of the structure, it may be pointed out that heavy metal castings are very largely dispensed with and in place thereof parts are fabricated from sheet metal with some parts of tubular form. Further, in accordance with the invention, heavy ceramic materials are avoided.

A furnace structure made in accordance with the invention is shown in the accompanying drawings:

Fig. 1 is a side elevational view of a burner constructed in accordance with the invention showing the same mounted in a furnace with some of the furnace structure shown in broken lines.

Fig. 2 is a view in section taken substantially on line 2—2 of Fig. 1 illustrating the burner tube and deflector plate.

Fig. 3 is an enlarged cross sectional view taken substantially on line 3—3 of Fig. 2 showing a mounting for the deflector plate.

The support for the burner advantageously comprises a member 1 and a cross piece 2 provided with floor engaging screw threaded studs 3 which are threaded into the cross support and the inner end 5 of the member 1 and which may be locked in position by nuts 4.

As shown in Fig. 1, a portion of a furnace is illustrated at 8 and the support is disposed to lie partially within an area 9 within the furnace. This is the lower part of the furnace and if the furnace previously used coal, the area 9 could have been the ash pit. The former grate level of the furnace is indicated at about the broken line 10 while the combustion chamber is illustrated at 11. The compartment 9 is to be closed and this may be done by two sheet metal members 13 and 14 secured together in their central portion by screws 15.

The mixing tube is shown in Fig. 1 as having an outer tube 20 provided with secondary air openings 21, primary air openings 22 and a gas jet member. The element 20 contains a suitable venturi, not shown, and is designed to telescopingly receive the main burner tube 45 which is

somewhat of L shape so that its free end extends upwardly as shown. The burner tube supports a baffle or deflector 50 preferably in the form of a pan shaped stamping of heat resisting metal such as one of the stainless steels. For this purpose there is a spider structure 51 (Fig. 2) which rests on top of the tube 45. The outer ends of the legs of the spider are turned downwardly as indicated and are secured to a ring or collar 52 to support the same in spaced relationship with the tube 45, thus providing an air passage space 53.

A post or rod 55 supports the deflector and is secured to the center part of the spider by nuts 54. An inverted socket 56 is secured to the center of the deflector for fitting over the top of rod 55. These parts advantageously rest upon the top of the tube by gravity so that they may be easily installed from a knocked down condition. To reinforce the structure a second spider 57 is arranged for the post 55 to pass therethrough and the ends of its legs as at 58 are secured as by means of welding to the collar 52. Since the spider 51 is depressed, the two spiders engage the post 55 at spaced points.

The described mixer tube and burner tube assembly is mounted on the support for which purpose the body member of the support is provided with a number of U-shaped brackets each shown at 60, and a series of clamps 61 (Fig. 1) are engaged around the exterior tubular form and are passed through the U-shaped brackets and tightened each by a screw (not shown). The two clamps 61 disposed within the furnace chamber 9 engage the tube 45 while the exterior clamp 61 engages the outer tube 20 and is of slightly larger size. The structure is disposed as shown in Fig. 1, with the tube 20 and the frame member 1 passing through the enclosing plates 13 and 14 with the parts so positioned that the secondary air apertures 21 are disposed just outside the closure plates 13 and 14.

As more fully disclosed in my above mentioned patent, a pilot burner 85 whereat a pilot flame 86 burns is supported adjacent the main burner. The pilot burner support has a struck out hook 81 which slidably fits over a track 70 whose inner end is mounted on tube 45 by a clamp 71. The extreme inner end of the track is folded back upon itself to provide a hook 72 to facilitate positioning the pilot burner support. Track 70 has an inclined intermediate portion 73 and extends out of the burner enclosure through plates 13 and 14. The outer end of the track is supported by a bracket 74 carried by support member 1. The pilot burner can be removed from and replaced in the burner chamber by sliding hook 81 outwardly and inwardly on track 70.

The operation is as follows: the fuel gas is projected in the form of a jet from a jet member into tube 20 and the venturi action therein causes a draft of air to enter the primary air ports 22 so that the proper combustible mixture of gas and air is obtained therein. This mixture passes into the tube 45 and upwardly where the flame burns at the upper and outlet end of the pipe 45. The flame thus burning upwardly strikes the diverter or baffle 50 and is spread outwardly in all directions in the fire box or fire chamber 11. Of course, suitable controls may be used for automatically governing the inlet of the gas but the controls constitute a separate art.

Secondary air is supplied to the flame through the control ports 21 located just outside the plates 13 and 14. The secondary air passes into the furnace chamber 9 and then upwardly by the convection currents. Some of this air passes through the space 53 and is guided in its upward movement by the guard or collar 52 and brought into direct supporting relationship with the combustible mixture at the upper end of the tube 45 with the result that combustion occurs in a region generally adjacent the periphery of the baffle 50 and above the baffle, thereby

providing a diffuse flame efficient for space heating purposes.

I claim:

In a gas burner for use with a heating furnace, a burner tube having an upwardly extending open end for the discharge of a combustible gaseous mixture, a spider-like element at the open end of the burner tube, said element having a plurality of radial legs with depressed central portions slidably fitting within the open end of the burner tube, said element having other radial legs secured to the first mentioned legs and lying in a plane spaced from the said depressed portions thereof, at least one set of legs extending radially outwardly from the burner tube and resting on the top end thereof, a collar carried by the outwardly extending legs and extending around the open end of the burner tube, said collar projecting both above and below the level of the open end to thereby define a passageway surrounding the open end of the tube for the passage of secondary air therethrough, said spider being

centrally apertured at the junctures of both sets of legs, a post engaging within the apertures for being supported by said element, a pan shaped deflector of sheet metal, said deflector having a central inverted socket removably engaging the top of said post to be supported thereby, said deflector overlying the open end of the burner tube for deflecting the flame of combustible gas outwardly relatively to the burner tube.
